COMBINED PAPER WEIGHT AND SPINDLE

Philip Hass, New York, N. Y.

Application October 11, 1955, Serial No. 38,321

Term of patent 14 years

(Cl. D74—2)

Fig. 1 is a front perspective view of a combined paper weight and spindle, showing my new design;

Fig. 2 is a side elevational view thereof, in folded position;

Fig. 3 is an end elevational view of Fig. 2; and

Fig. 4 is a top plan view of Fig. 2.

I claim:

The ornamental design for a combined paper weight and spindle, as shown.
